EXHAUST FAN

Joseph M. Barrett, East Cleveland, Ohio

Application March 21, 1932, Serial No. 600,194

4 Claims. (Cl. 98—43)

This invention relates to the art of exhaust type ventilating fans for kitchens or other rooms where cooking odors, steam vapors, etc. are to be removed.

5 In its preferred form the invention forms an integral part of the pipe connection between stove and chimney (sometimes termed the flue connection). However, the invention may be applied to any room having a flue connection or 10 outlet. While particularly adapted to cooking stoves utilizing gas, it may however be used when electricity is the heating agent and will function to remove room vapors or odors to the outside atmosphere.

15 Common practice is to place an exhaust type ventilator in a window opening and when such a fan is operated the vapors and odors are carried across the room and discharged to the exterior. Due to the location relative to the stove only a part of the odor-laden air is evacuated 20 from the room. Air currents ordinarily follow the line of least resistance in the room and some of the warm odor-laden air rises from the stove and spreads throughout the room and house 25 without being carried to the outside by the fan. Furthermore, during inclement weather the window must be opened and closed each time the fan is used, or if the wind is blowing toward the window then a condition may occur where 30 the fan will not evacuate any air from the room.

With the use of my invention the gathering point for the vapor and odors is in the immediate vicinity of their formation, and as a result the odor or vapor-laden air has the shortest distance to travel before it is evacuated. The incoming air from other parts of the room or house, moving toward the fan location, provides a blanket that helps to keep the odors from penetrating, away from the stove, into the room and 40 the remainder of the house. The use of my exhaust fan eliminates the drawing of smoke, odors and grease-laden air across the room from the stove to a window and for this reason eliminates having dirt and scum deposits around the 45 window and draperies.

The use of an exhaust type fan connected to a chimney flue without proper safeguard would of itself prove more or less inefficient and a possible hazard. For example, where gas is used 50 as a fuel the average installation has no provision for a balanced chimney draft, so that when gusts of wind occur, the momentary increase in the chimney draft has a tendency to snuff out pilot flames and burner flames in ovens, even when the oven is controlled by a heat regulator.

A primary object of my invention is to provide an arrangement of apparatus automatically effective to protect the oven or ventilated space from changes in draft at the outlet of the flue, whether such variations in draft, which otherwise might 5 be effective upon the ventilated space, be caused by changes in the natural draft at the flue outlet or by changes in the artificial draft beyond the automatic means.

An important feature of my invention is the 10 use of a synchronous motor for driving the fan, thereby reducing the space required for the motor and furthermore providing a noiseless driving means without sparking or effect upon radio reception when the fan is operating. 15

A principal object of the invention is to provide a complete evacuating unit that becomes an integral part of the flue connection between the stove and the chimney and one that for installation requires only the removal of a section 20 of the existing stove pipe, the insertion of the length of stove pipe containing the fan means, and then the plugging in of the electrical connection to any convenient outlet. The various 25 adjustable elements allow making a permanent setting of the device so that it will function satisfactorily when operating under draft conditions peculiar to each installation. When once adjusted for a fixed set of operating conditions it will stay in adjustment. The overall cost of 30 production and manufacture is relatively small, which in turn allows a reasonable or low retail price.

In the drawing:

Fig. 1 is a partially sectioned front elevation 35 at C—C of Fig. 2.

Fig. 2 is a side sectional elevation at A—A of Fig. 3.

Fig. 3 is a partially sectioned plan along the 40 line B—B of Fig. 2.

Figs. 1, 2, and 3 are the principal views of one form of the device, whereas Figs. 4, 5, 6, and 7 show details, to an enlarged scale, of the arrangement of Figs. 1, 2 and 3.

Fig. 8 illustrates in diagrammatic fashion 45 another preferred embodiment of the general arrangement.

The flue connection, or length of stove pipe for connection between the oven and chimney flue, is shown at 15. The motor 9 is mounted in and protected by housings 10 and 13 so as to eliminate dirt and scum collecting on the motor; and may be connected by a conductor 14 with a source of electricity. The bearings of the motor may be oiled by the element 8 which leads from the mo- 50 55

tor bearing to the exterior of the housing 13 and having small outlets 8a to distribute oil to each bearing. The housing 13 is attached to the flue 15 in any approved manner and is open at 19 to allow ingress of air to the fan.

A damper 6 is hinged as shown by elements 2, 3 and angularly moves around the shaft 18. The lower end of the damper has a counterweight 17 which may be removable and of such construction that its total weight can be varied by adding to or cutting off a part of it. The object of the counterweight 17 is to provide the required balance for the damper 6 so that when the damper is not in an inclined position, as in Fig. 2, it will assume a closed or semiclosed position dependent on the location of a stop 12 and a locking device 5. Dotted line 6a of Fig. 2 shows the damper in a vertical position or what may be termed the closed position, and wherein the locking device 5 is shown as holding it in that position. To lock damper 6 in an intermediate position as shown in full line in Fig. 2, the locking device 5 is turned to the dotted line position so that counterweight 17 lies substantially between 12 and 5b. To lock damper 6 in a closed position, counterweight 17 lies substantially against 5c, as shown in dotted line in Fig. 2.

When the fan is operating, its artificial draft causes the damper to swing partially open; and during fan operation, the damper continuously and automatically positions itself in a more or less inclined position, dependent upon the relation of pressures acting upon its faces. All variations in draft toward the flue outlet, whether caused by the natural or the artificial drafts, act upon the damper to cause it to automatically assume a position representative of draft effects. By its self adjustment as to position it protects the flue inlet and likewise the oven or ventilated space from varying effects of the natural and/or artificial draft. The outflow of gases past the damper from the oven or ventilated space remains substantially constant or dependent upon the amount and temperature of the gases to be so ventilated; for, the area opening between the flue wall and the end of the damper 6 varies at the same time as the effective draft upon this opening, so that with an increased draft and reduced opening the net suction effect or flow from the oven is substantially the same as with full flue opening and reduced draft at the damper outlet.

The embodiment includes an adjustable stop 12 for limiting the maximum deflection or opening of the damper when the fan is operating, as in the positions 12a or 12b. In this manner proper opening always exists for the exit of products of combustion, the damper being counterweighted, so that when it is not held in an inclined position due to the air force from the fan, it will assume a closed position, thus closing the opening between the inside of the flue and the room proper.

Provision is also made for locking this tilting damper or closure device, in an intermediate or fully closed position. This feature will allow the setting for a minimum opening of the damper so that a fixed amount of air will pass to the flue when the fan is not operating. I also provide an automatic means for limiting the amount of natural draft effective at the point of combustion when the tilting damper is left in an unlocked position. In this instance any partial vacuum in the chimney flue caused by a gust of wind will not affect the flame, for the vacuum is broken by the tilting closure device, or damper, which in so tilting toward the inside of the flue, due to the

greater pressure on the room side, restores atmospheric pressure on the inside of the flue.

The locking device 5 is frictionally mounted on the lower end of a stud 11 in a manner such that it may be rotated around the stud 11 by hand, preferably to the two positions illustrated in Fig. 2, the one 5 in solid line and the other 5a in dotted line. 19 indicates an opening to the housing 13 through which the air enters to the fan and through which a person's hand may move to grasp the locking device 5 by the projections 5b and 5c and move it from one position to another.

The damper 6 in its closed or dotted position 6a is shown to just meet the projection 4 and close the opening to the housing 13. In all positions of opening, the projected height of the damper is less than the height of the opening of the housing into the flue. Likewise baffle 20 of Fig. 8 is shown as not extending in height completely opposite the opening of the housing into the flue. 20

If the damper 6 in operating position, or the baffle 20, extended beyond the opening, the passage for air from the housing to the flue would be restricted and the air from the fan would have a tendency to mushroom and cause back pressure upon the fan, thus cutting down its efficiency. 25

If no damper 6 or baffle 20 were present in the construction, the air from the fan would impinge upon the far wall of the flue 15 and in mushrooming back would create a downward pressure 30 toward the oven or heated space with a tendency to snuff out the flame or force gases out into the room.

I have found that an intermediate condition of having the baffle, or the damper, in operating position somewhat shorter than completely coextensive with the opening is the most practical and efficient design and have so shown in Figs. 2 and 8. 35

When the fan blades 1 are operating, the air forced into the flue 15 is deflected by the damper 6 and its course changed as shown by the arrows, causing a forced draft in that portion of the flue above the damper 6. This, of course, is caused by the increase of velocity of the air passing up 40 the flue from the fan over that passing through the flue under natural draft conditions. The increased amount of air entering the flue from the fan and thereby the increased air velocity, in the flue above the damper, also serves to cause an induced draft or partial vacuum in that portion of the flue under the damper 6, and for this reason the damper 6 may be tilted and occupy the majority of the cross sectional area of the flue 15 and at the same time as much or more products of combustion can pass through the area 16 as if the damper 6 were not interposed across part of the cross sectional area of the flue 15. Having an increased air velocity above the damper causes what is known as a Venturi action at 55 the area 16, thereby increasing the velocity of the air current passing through the area 16. 60

When the fan is disconnected and stops running, the counterweight 17 will force the damper to a position shown by the dotted line 6a and the damper 6 will then make contact with plate 4 and in this manner close the opening which previously existed between the housing 13 and the flue 15. In some instances it may be desirable even with 65 the fan running to have a reduced volume of air removed, and in this instance the damper 6 may be locked in an intermediate position through the use of the device 5. There will also be instances when the fan is not running that an opening be- 70 75

tween the inside of the flue and its exterior will be desirable and this can be accomplished by tilting the damper 6 and holding it in its tilted position by the locking means 5.

5 In the average installation when the locking device 5 is in the position shown by the full lines of Fig. 6, then with the fan blades not rotating any excess chimney draft will tend to tilt the damper 6 inward and thereby allow air exterior to the flue to enter the flue and in this way break the momentary vacuum which may exist. This function of the damper will eliminate the hazard of a sudden increase in chimney draft snuffing out pilot lights or flames whose products of combustion are accessible to the flue connection.

It will be observed that the action of the damper 6 is automatic when free from the locking device 5. Normally the counterweight 17 moves the damper 6 to its closed or dotted position when the fan is not running. Gases from the oven may freely pass upward through the flue 15 as in the ordinary kitchen installation. If, however, there is a sudden suction or vacuum from the chimney the damper 6 will be pulled inwardly and the tilted position will tend to protect the oven from the vacuum of the chimney and at the same time the rush of air from the room through the opening caused by the opening of the damper 6 will tend to break the vacuum. If the fan is running, the force of its ejected air will cause the damper 6 to tilt to a partly open position and a current of air as indicated by the arrows will be moved from the fan upwardly and at the same time a relatively parallel current of air will flow upward through the flue 15 at the left-hand side of the damper 6 from the oven or other connected space. Thus there will be substantially two parallel flows of air at opposite sides of the damper 6 joining above the damper 6 to form a single flow whose volume and velocity is influenced both by the natural draft suction of the chimney and by the forced draft effect of the fan. The suction at the oven, however, due to the automatic positioning of the damper 6, is not materially varied no matter what the variation is in the natural draft suction of the chimney or the forced effect of the fan.

50 Referring now to Fig. 8, I illustrate therein a fixed baffle 20 which fails to completely occupy the projected area of the housing 13 and serves a purpose similar to the damper 6. This may be used in place of the tilting damper and is so proportioned as to be the equivalent of the tilting

damper 6 under normal conditions of operation.

Having thus described the invention, what is claimed is:

1. A system of ventilation comprising means for producing a natural draft, means for producing a flow of gases by artificial draft, the natural draft and artificial draft jointly effective in producing a second flow of gases, the two flows substantially parallel for a portion of their travel, and means automatically effective for maintaining substantially uniform the draft value of the second flow regardless of changes in value of the natural draft. 5

10 2. In combination, a chimney flue having an inlet and an outlet and having an opening in one side, a housing surrounding the opening and having an open side, fan means located within the housing and adapted to draw gases through said open side and to discharge to said flue, and means within the flue adjacent the housing and automatically effective when the fan is operating tending to maintain the draft at the inlet to the flue constant regardless of variations in draft at the outlet of the flue. 15

20 3. In combination, a chimney flue having an inlet and an outlet and having an opening in one side, a housing surrounding the opening and having an open side, power driven fan means located within the housing and adapted to draw gases through said open side and to discharge to said flue, and a damper within the flue adjacent the housing pivoted to swing inwardly under impact of the air from the fan and automatically effective when the fan is operating tending to 25 maintain the draft at the inlet to the flue constant regardless of variations in draft at the outlet of the flue. 30

35 4. In combination, a section of stovepipe connected to an oven and having an opening in one side, a housing surrounding the opening and having an open side, fan means located within the housing and adapted to draw air and gases through said open side and to discharge into said stovepipe, and a baffle joining the inner wall 40 of the stovepipe adjacent the bottom of the opening and positioned substantially opposite the opening to restrict the passage of gases from the oven past the opening thereby increasing their velocity at that point while allowing gases from the housing to enter the stovepipe at the upper 45 end of the baffle, the baffle not extending opposite the opening to the complete extent of the opening. 50
